CASEMENT WINDOW LOCK

Michael J. Clapp, Brooklyn, N. Y., assignor of
one-third to Alexander R. La Guardia and one-
third to Paul M. La Guardia, both of Brooklyn,
N. Y.

Application December 28, 1946, Serial No. 719,079

2 Claims. (Cl. 70—89)

1

This invention relates to locks for casement windows or the like.

It is the primary aim and object of the present invention to provide a lock which is particularly suited for windows of the type generally known as "French" windows, and which is so inconspicuous as to its function as a lock that it neither appears to the casual observer as a prominent part of the window, nor is it readily discernible by a burglar.

It is another important object of the present invention to provide a lock of the above characteristics which is of simple and rugged construction, and which may easily be shaped to fit harmoniously into the general design of a window.

The above and other objects, features and advantages of this invention will be fully understood from the following description, reference being had to the accompanying illustrative drawings.

In the drawings:

Fig. 1 perspectively shows the present invention embodied in the latch members of a pair of casement windows;

Fig. 2 is a side elevation of the latch members as viewed in the direction of the arrow 2 in Fig. 1;

Fig. 3 is a longitudinal section through the lock employed in the invention; and

Fig. 4 is a section taken on line 4—4 of Fig. 3.

Referring to the drawings, and particularly to Fig. 1 thereof, the reference numerals 10 and 12 designate casement windows which, in the present instance, are of the type known as "French" windows. Each of these windows comprises a sash 14 and suitably arranged glass panels 16. Windows of this type are customarily hinged on a framework so as to open either outwardly or inwardly. In the present instance, the windows 10 and 12 are arranged so as to open outwardly. Further, windows of this type are usually arranged in pairs, the opposite sides of which are hingedly mounted on the framework, while the adjacent sides thereof carry on the inside conventional latching means 18 by means of which these windows are held closed against an intermediate jamb 20 of the framework. The latching means 18 are identical for each window, each comprising a latch handle 22 which is pivotally mounted at 24 on a bracket 26, riveted or otherwise secured at 28 to a mounting portion 30 of a window. Each latch handle 22 is also provided with a latch finger 32 which cooperates with a keeper 34, having the cus-

2

tomary wedge surface 36 with which the latch finger cooperates to hold a window closed tightly. The keeper 34 is mounted in any suitable manner on the jamb 20. Each window may be opened after turning its respective latch handle 22 from the latching position shown in Fig. 1 into non-latching position, and may be latched, when closed, by turning the latch handle 22 into the latching position shown in Fig. 1.

10 In accordance with the present invention, there is provided a lock 40 which is divided into two complementary sections 42 and 44 that are carried by the latch handles 22, respectively. More particularly, the lock sections 42 and 44 comprise casings 46 and 48, respectively, which may suitably be secured to, or made integral with, the latch handles 22, respectively. The casing 46 is preferably provided with an inwardly offset, open end 50 which fits into the adjacent open end of the casing 48 when the sections 42, 44 are in the closed position shown in Figs. 3 and 4. Permanently mounted in any suitable manner between spacers 52 in the casing 46 is a catch 54 which is adapted to interlock with a bolt 56 in the casing 48 in order to lock the sections 42, 44 in their closed position. The bolt 56 is pivotally mounted at 58 in the casing 48, and is normally urged into interlocking relation with the catch 54 by means of a leaf spring 60 which is held in place in a spring seat 61, suitably mounted in the casing 48. The bolt 56 may be rocked out of interlocking relation with the catch 54 by a cam lug 62 on the revolving plug 64 of an auxiliary lock 66 which is, in the present instance, in the form of a Yale type cylinder lock. This lock comprises also a cylinder 68 (Figs. 3 and 4) which is suitably secured at 70 in the casing 48 and rotatably supports the revolving plug 64, the latter being held against axial removal therefrom by a screw 72, threadedly received in the cylinder 68 and projecting into an annular groove 74 in the plug 64. The cylinder 68 is peripherally slotted as at 76 to admit the bolt 56 into cooperative relation with the cam lug 62 on the plug 64. The revolving plug 64 is provided with a longitudinal groove 78 for the insertion of a key (not shown) with which to operate the customary spring-urged tumblers 82 in the auxiliary lock 66 to release the plug 64 from its locked relation with the cylinder 68 (see full-line position of plug 64 in Fig. 3) and permit it to turn. On inserting the key, the same may be turned so as to turn the revolving plug 64 into the dot-and-dash line position shown in Fig. 3, whereby the cam lug 62 forces the bolt

56 into the dot-and-dash line position shown in the same figure, i. e., out of interlocking relation with the catch 54. The latch handles 22 may then be turned on their pivots 24 in the direction of the arrows 90 and 92, respectively, in Fig. 1 into position to release the windows 10, 12 for outward opening. Also, either window 10 or 12 alone may be opened when the lock 40 is opened in the previously described manner. Thus, window 12 may, for instance, be opened after opening the lock 40, by rocking latch handle 22' in the direction of the arrow 92 in Fig. 1 toward and beyond the dot-and-dash line position there shown, until the latch finger 32 on the handle 22' clears the keeper 34', whereupon the window 12 may be swung outwardly. The auxiliary lock 66 may also be provided with a spring (not shown) which normally returns the revolving plug 64 into the full-line position shown in Fig. 3, so that lock 40 will close automatically when both latch handles 22 on the closed windows 10, 12 are turned into their respective latching positions as shown in full-lines in Fig. 1.

It appears from Fig. 1 that the latch handles 22 are, in the present instance, constructed for left and right hand operation, respectively, so that these handles approach each other when turned in opposite directions into their respective latching positions, thereby rendering them particularly suitable for the embodiment of the lock 40 to the end that the latter is closed when the latch handles 22 are turned into their respective latching positions. Also, mounting the lock sections 42, 44 on the ends of the latch handles 22 tends to render the lock 40 inconspicuous as to its function as such, and affords the opportunity to form the lock sections 42, 44 so that they fit harmoniously into the general design of the latch handles 22. The lock sections 42, 44 may even be formed to appear to an observer as ornamental parts of the latch handles 22.

While the present locking device has, by way of example, been described herein in conjunction with casement windows, it is to be understood that the same may be used with equal advantage on hinged doors or other similar closures.

Having thus described my invention, what I claim and desire to secure by Letters Patent is:

1. A locking device for a pair of hinged closure members closable against an intermediate jamb comprising, elements pivoted on said members, respectively, on the adjacent sides thereof and turnable in opposite directions for releasably latching the closed members to said jamb, said elements having handle portions, respectively, approaching each other on turning said elements into their respective latching positions, and a lock comprising complementary sections carried by said handle portions, respectively, said sections comprising casings, respectively, holding parts, respectively, which interlock with each other on turning said elements into their respective latching positions, and key-operated means carried in one of said casings for releasing said parts from interlocked relation with each other.
2. A locking device for a pair of pivotally mountable left and right hand latch members of the type adapted to swinging closure members, respectively, comprising a lock having complementary sections carried by said latch members, respectively, and comprising parts, respectively, which are relatively movable to and from interlocking relation with each other when said members are disposed in their mounted relation to each other and assume their respective latching positions, and means for relatively moving said parts to and from interlocking relation with each other.

MICHAEL J. CLAPP.
